UNITED STATES PATENT OFFICE.

HARVEY H. BURRITT, OF NEWARK, NEW JERSEY.

AIR-ENGINE.

SPECIFICATION forming part of Letters Patent No. 278,897, dated May 29, 1883.

Application filed March 21, 1883. (No model.)

To all whom it may concern:

Be it known that I, HARVEY H. BURRITT, a citizen of the United States, residing at Newark, in the county of Essex and State of New Jersey, have invented certain new and useful Improvements in Hot-Air Engines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to that class of engines known as "air-engines," and has for its object a greater efficiency of action and simplicity of construction in such engines.

The invention consists of such an arrangement and combination of parts as will be hereinafter set forth, and finally embodied in the claims.

In the drawings, in which similar letters of reference indicate like parts in each of the several figures, Figure 1 is a side elevation of an engine embodying my invention, partly in section. Fig. 2 is a front elevation of the same, parts of which are broken away. Fig. 3 is a section taken through line *x* of Fig. 2.

The motive power in this engine and in those similar to it is due to the expansion and contraction of a body of air confined in a cylinder having therein a working-piston, *a*, Fig. 1, and what may be called an "exchange" or transfer piston, *b*, by which the inclosed air is transferred from one end of the cylinder to the other, said transfer-piston having an annular chamber between it and the surrounding cylinder for the passage of air. The heat for the expansion of the air is applied below the cylinder, either coal, gas, or other suitable fuel being used, as may be convenient or desirable.

In the drawings, *a* is the working-piston; *b*, the transfer-piston. The working-piston *a* is connected to the arm *c* by links *d*, the arm *c* projecting from an encircling shaft, *f*, which is keyed to the rock-shaft *e*, and at the other end of the encircling shaft *f* projects the arm *g*, which is connected with the driving-wheel *h* by the rod *i*, as shown. The transfer-piston is connected with the rocking arm *k* by the rod

b', which passes through the working-piston *a*, being provided with a stuffing-box in the top of the working-piston, and the rod *l*, said rocking arm *k* and rod *l* moving between the links *d*, the end of the arm *c* being curved, so as to permit the oscillation of the arm *k*. The arm *k* works freely upon the rock-shaft *e* by the sleeve *m*, from which extends the curved rocking arm *n*, which is connected by the rod *o* to a crank, *p*, on the end of the driving-wheel shaft on the opposite side of the engine, as shown in Fig. 2. To the same crank *p* is pivoted the rod *q*, which is attached to the plunger of the pump *r*. Within the outer casing is an inner cylinder, *a'*, in which the working-piston moves, extending downward within the body of the casing about the length of the stroke of the working-piston *a*. Around the working-piston cylinder, inside the casing, and extending down below the end of the inner cylinder, is a coil of pipe, *s*, circling around the transfer-piston and connected at the lower end, or, if desirable, at the upper end, with a pump. The other end of the coil, passing out through the casing of the engine, may be connected with a pipe leading to a cistern or reservoir or a tank to supply water for domestic or other purposes, as desirable.

The operation of the parts is substantially as follows: The transfer-piston, being on its upward movement, forces the air to the lower end of the cylinder, where it is heated, expands, and forces the working-piston upward. While the working-piston is moving upward the transfer-piston moves downward and forces the hot air to the upper part of the cylinder, where, coming in contact with the cold pipes, it is cooled, contracts, and thus allows the working-piston to descend. The transfer-piston again moves upward, and the operation is repeated. The movement of the working-piston is communicated through the links *d*, rocking arm *c*, encircling shaft *f*, rock-shaft *e*, rocking arm *g*, and the rod *i* to the driving-wheel, from the driving-wheel through the driving-wheel shaft to the crank *p*, rod *o*, rocking arm *n*, sleeve *m*, rocking arm *k*, rod *l* to the transfer-piston, the parts being so adjusted and arranged that a stroke of the working-piston is one-half that of the transfer-piston.

Cold water, or any other cooling medium, is kept circulating through the coil by the pump *r*, which is operated from the crank *p* through the rod *q*. If desirable, the water may be supplied from a tank.

In other air-engines the air is cooled by coming in contact with a water-jacket in which a solid body of water is kept around the hot-air cylinder, this arrangement affording a limited cooling-surface. By the use of a coil a much greater cooling-surface is secured, as the air circulates all around the pipes, and by thus increasing the difference in temperature the power of the engine is greatly increased. Moreover, the walls of the pipes may be made much thinner than those of the water-jacket, thus producing a more effective cooling-surface. The suction side of the pump may be connected to the coil, thus reducing the pressure.

15 The coils may be made of brass, wrought-iron, or other material, as may be desirable.

My invention may be used for pumping water, or for any other purpose to which an engine is applicable.

25 Having thus described my invention, what I claim as new, and wish to secure by Letters Patent, is—

1. In an air-engine, the combination, with the cylinder, driving-wheel, and shaft, of a 30 working-piston, *a*, inner cylinder, *a'*, links *d*, encircling shaft *f*, having arms *c* and *g*, said shaft being keyed to a rock-shaft, *e*, and a connecting-rod, *i*, all substantially as set forth.

2. The combination, with the cylinder, driving-wheel, shaft, and a crank, *p*, of an air-en- 35

gine, of a transfer-piston, *b*, rod *b'*, connecting-rod *l*, sleeve *m*, having arms *k* and *n*, rock-shaft *e*, and connecting-rod *i*, all substantially as set forth.

3. In an air-engine, the combination, with 40 the cylinder, driving-wheel, shaft, and a crank, *p*, of a working-piston, *a*, inner cylinder, *a'*, links *d*, encircling shaft *f*, having arms *c* and *g*, rock-shaft *e*, connecting-rod *i*, and a transfer-piston, *b*, rod *b'*, connecting-rod *l*, sleeve *m*, 45 having arms *k* and *n*, and a connecting-rod, *o*, all substantially as set forth.

4. The combination, with the cylinder of an air-engine, of a coil of pipe, *s*, and means for circulating a cooling medium through the 50 same, all substantially as set forth.

5. In an air-engine, the combination, with the cylinder or shell and an inner cylinder, *a'*, a working-piston, *a*, and a transfer-piston, *b*, of a coil of pipe, *s*, and a pump, *r*, all substantially as set forth. 55

6. The combination, in an air-engine, of a pump for pumping water, and a coil of pipe, connected with said pump either by suction or delivery, so as to cause a circulation of water 60 through the said coil of pipe, all substantially as set forth.

In testimony that I claim the foregoing I have hereunto set my hand this 13th day of March, 1883.

HARVEY H. BURRITT.
